United States Patent Office

Des. 215,341
Patented Sept. 23, 1969

215,341

LIGHTING FIXTURE

Gerard Edmund Mulvey, 36 Castle Frank Road, and
George Elliott Boake, 6 Maple Ave., both of Toronto,
Ontario, Canada

Filed Jan. 16, 1968, Ser. No. 10,188

Term of patent 14 years

Int. Cl. D26—02

U.S. Cl. D48—23

FIG. 1

FIG. 2

FIG. 3

FIG. 1 is a bottom perspective view of a lighting fixture embodying our new design;

FIG. 2 is a sectional elevation along the line 2—2 of FIG. 3, and,

FIG. 3 is a bottom plan view of the lighting fixture, the top half being broken away for convenience of illustration.

The dominant features of our design reside in the portions shown in full lines.

What we claim is:

The ornamental design for a lighting fixture, as shown and described.
